United States Patent Office

Des. 206,246
Patented Nov. 15, 1966

206,246

BOTTLE TOP

Robert E. Watson, Farmington, Mich., assignor to Swedish Crucible Steel Company, Detroit, Mich., a corporation of Michigan

Filed May 26, 1965, Ser. No. 85,466

Term of patent 14 years

(Cl. D58—26)

FIG. 1

FIG. 2

FIG. 3

FIG. 4

FIGURE 1 is a top plan view of a bottle top, showing my new design;

FIGURE 2 is a front elevation of the design of FIGURE 1;

FIGURE 3 is a side elevation of the design of FIGURE 1; and

FIGURE 4 is a bottom plan view of the design of FIGURE 1.

I claim:

The ornamental design for a bottle top, as shown.
